UNITED STATES PATENT OFFICE

JOHN L. McMILLAN, OF SYRACUSE, NEW YORK, ASSIGNOR TO Mc MILLAN BOOK COMPANY, OF SYRACUSE, NEW YORK, A CORPORATION OF NEW YORK

LOOSE-LEAF BINDER

Application filed January 19, 1925. Serial No. 3,429.

This invention pertains to that class of loose leaf binders commonly used for minute books, record books, and the like, and employing a back and cover-boards provided at or 5 near the hinge lines connecting the boards and the back, with metallic housings firmly secured to the cover-boards, and each having a tubular portion provided with openings to receive the perforated ends of links which 10 receive the perforated ends of links which bridge the space between said members, and upon which are threaded or strung suitably 15 perforated sheets making up the book. The tubular portions contain longitudinally movable bars provided with hinge-pins or pinc 20 tles of a length somewhat greater than the openings made to receive the link ends, so that when properly adjusted the hinge-pins pass through the links, bridge and reach beyond said openings, and are covered or housed 25 within the tubular portions.

The invention is directed particularly to means for locking the sliding bars, thus preventing removal of a leaf or leaves, or the introduction or substitution of leaves, except 25 by, or through co-operation of, the custodian of a key controlling the locking device.

Record and minute books require to be well protected against falsification through substitution of leaves, or removal, alteration, and replacement of leaves. Though sometimes written in long-hand, such minutes and records are now quite commonly typewritten. Whether the records be pen written or typewritten, it is much more convenient to have 35 the sheets entirely free and out of the binder while making entries, and mechanism is accordingly provided for normally locking the binder, and for unlocking the same when necessary to remove, insert, or replace leaves. 40 Several types of locking devices have been employed for this purpose, but so far as I am aware, none of these has proven entirely satisfactory. The construction which I shall 45 now describe in connection with the accompanying drawings, is believed to meet all requirements, and is simple, strong, and secure. In these drawings:

Figure 1 is a perspective view on a reduced 50 scale showing a book embodying my inven-

tion, opened to display the exposed parts of the mechanism;

Figs. 2, 3 and 4, face elevations of one of the cover-boards, showing the metallic housings, its contained sliding pintle bar, and the lock by which said bar is held against longitudinal movement, the parts being shown in the different positions they assume in operation;

Fig. 5, a perspective view of one of the metallic members in which the sliding pintle bar and the locking mechanism are mounted showing one of the leaf-carrying links in position;

Fig. 6, a perspective view of the sliding 65 pintle bar;

Fig. 7, a view showing the lock-bolt slightly protruded from its casing, and holding back the detent.

In these drawings, 1 indicates the binder 70 comprising a back 2 and two cover-boards 3 and 4, each having the hinge connection with the back common to book bindings generally, that is to say, formed by flexible material (leather, fabric, or other), and without any 75 contained board or stiffening in the flexing part proper. Any usual type of hinge joint connecting the back and the boards may be employed. Firmly secured to the inner edge or margin of each cover-board is a metallic 80 housing 5, conveniently and preferably formed of sheet metal suitably stamped and folded to produce at the folded edge a substantially complete hollow cylinder or barrel 6. This barrel is cut away at intervals to 85 produce seats or openings 7, each to receive one end of a link or leaf-carrying bar 8, three such links being provided for in the accompanying drawings but the number being variable as desired, from two upward. 90

Within the metallic housing 5 and at the inner or folded side thereof, is a longitudinally movable pintle bar 9, the inner edge of which is thickened or provided with a bead 10 of rounded or cylindrical form, and of a 95 diameter to produce a free sliding fit within the barrel 6. At suitable intervals in its length the inner edge of the bar 9 is cut away as shown in Fig. 6, to leave gaps or openings 11 equal in length to the length of the open- 100

ings 7 in the barrel 6, and to produce pintles 12 as seen in said figure. The bar 9 is further provided on the edge opposite that on which the pintles 12 are formed, with a notch 5 or seat 13 to receive the end of a lock bolt 14 and a detent 15, which latter at certain times engages over the outer end of the lock bolt and holds said bolt against movement outward from its casing 16. Bar 9 is also furnished with a serrated button or plate 17 provided with a stem or shank which passes through an opening 18 in the metallic housing 5, the stem allowing for the thickness of said housing, and permitting the button 17 to lie above the same in convenient position to be moved by the thumb or finger, and thus to slide bar 9 longitudinally.

The lock shell or case 16 is riveted or otherwise made fast to the housing 5, the cover-board being cut away to afford space for said lock case. The lock here shown is of the well-known Yale type employing a flat key 19, one longitudinal edge of which is fashioned to act upon tumblers 20 having slots to receive a rib 21 of the bolt 14 when the tumblers are thrown by the key to aline their slots with said rib 21. This type of lock is preferred because of its compact form, and of the vast number of different combinations or permutations of tumblers and key possible within a limited space. The detent 15 is mounted within the lock-case in addition to the bolt and tumblers, and is normally urged toward the lock-bolt by a spring 22, but is limited in its movement by a stop 23, the overhanging free end of the detent 15 swinging toward and engaging or overhanging the outer end of the lock-bolt 14 when the latter is retracted by turning the key 19, which key is seen in section in Figs. 1 and 2 and in perspective in Fig. 5.

When the pintle bar 9 is given a full movement longitudinally to the right with the parts arranged as shown in the several figures of the drawing, the pintles 12 are projected across the openings 7, as seen in Fig. 3, bridging said spaces and passing through the perforations 24 of the links 8. As before mentioned, under this construction and arrangement the free ends of the pintles 12 extend beyond the openings 7 and beneath the barrels 6, thus affording a firm hold for the pintles against stress or pull upon the links 8. When the bar 9 is thus shot or moved to link-retaining position, the lock-bolt 14, under the expansion or pressure of a spring 25, is thrown outward into the notch or seat 13 of pintle bar 9, as shown in Fig. 2, the detent 15 at such time being thrown to the left and prevented by the lock-bolt 14 from swinging to the right. The longitudinal movement of bar 9 in locking direction is limited by the shank of button or plate 17, and also by detent 15, hence said bar will be arrested in its movements back and forth either by the detent 15

or by lock-bolt 14 if the latter be projected. The bar can in no case be withdrawn from the housing 5 except through force sufficient to break the parts of the mechanism.

When the key 19 is inserted and swung in the arc of a circle, it forces back the tumblers 20 and draws down the bolt 14 clear of its seat in bar 9, whereupon the detent 15, under the force of spring 22, moves to the right until arrested by the stop 23 which it overhangs sufficiently to stand in the path of and engage the outer end of the retracted bolt 14, thus preventing said bolt from moving outward even though the key be turned to its entering position and withdrawn from the casing. The bar 9 is thereupon moved longitudinally to the left, thus withdrawing the several pintles 12 simultaneously from the respective links 8 and releasing them, but as bar 9 completes its full leftward movement, the right-hand end wall of the notch or seat 13 engages the overhanging end of detent 15, forcing the same back and clear of the bolt 14 which, under the force of spring 25, moves outward into contact with the under side of the pintle bar.

In Fig. 4 the bar 9 is shown at about the midlength of its movement to the left or in the direction indicated by arrow in said figure, but it will be obvious that continuation of the movement will force back the detent 15 and release the lock-bolt 14, which will then bear against the edge of pintle bar 9 and hold it against accidental shifting or displacement. This is advantageous in that it prevents the pintle bar from sliding forward of its own weight in handling the binder while the links are freed at one end, and thereby preventing the proper replacement and locking of the links.

The operation of the device will, it is believed, be clearly understood from the foregoing description, and as before indicated, it is intended that each book shall have a lock requiring a key unlike that of any other lock, so that the book may be unlocked only by the proper custodian of its special key. In operating the device the bar 9, when unlocked, should be moved its full distance in the link-releasing direction so that the lock-bolt 14, under the urge of spring 25, may rise slightly in front of the overhanging end of detent 15, when said detent is forced back by the right-hand end wall of seat or notch 13. The lock-bolt will thus prevent re-engagement of the detent over the end of the bolt, so that when the pintle bar 9 is again moved its full distance in locking direction, lock-bolt 14 may enter its seat 13 and lock the bar. This slight movement of bolt 14 into the path of detent 15 when the latter is forced to the left, is permitted by the slight distance between the outer end of the retracted bolt and the proximate edge of the bar 9.

It is deemed desirable to provide the binder

both at front and rear with a pintle bar and locking means such as here described, in order that either cover may be freed at will, and leaves be inserted or removed at the front or at the back of the book, as may be more convenient in any particular case. It is obvious, however, that one pintle may be permanently secured in place, in which case the pintle may be simply a continuous wire passing through one end of each of the several links, and made fast in the metallic housing 5 in any convenient way. This would, of course, permit application and removal of the leaves from one end of the links only, and is not deemed desirable.

It may in some cases be found expedient to employ for the front and rear pintle bars, locks requiring different keys to be held by different custodians, so that either may in the absence of the other, unlock the binder sufficiently to permit insertion or removal of leaves. The invention contemplates the use 20 at will of one or of two locking bars, and of locks operable by like or by unlike keys.

From the foregoing description it will be seen that the pintle bar is directly and manually actuated to move it into and out of locking engagement with the sheet-carrying links, and is locked and released by a separate and 25 distinct lock-bolt, controlled by a key, which performs no other function. This I believe to be broadly new in loose leaf binders.

It is particularly to be noted that under the above described construction the key may 30 be inserted into the lock, the lock bolt withdrawn, the pintle bar moved in link-releasing direction, and the key withdrawn. This allows the custodian of the key to release the links and permit insertion or removal of the sheet or sheets by the typist or other trusted employee, while said custodian may take the key away, the links being again engaged and the pintle bar locked through the mere sliding of said bar its full distance in pintle-engaging direction. The custodian of the key 35 is thus enabled to have the key always in his possession, while permitting the typist or other employee to do whatever is necessary, and then to lock the binder without the aid of said key. It likewise allows the leaves or 40 sheets to be laid flat upon the cover-board as they are removed from the links, which could not be done were the key left in the lock.

It is to be understood that the term "seat" 45 as applied to the notch or recess in each pintle-carrying bar contemplates any seat in or on any convenient portion of the bar, though the simple notch in the edge of the bar is preferred.

60 What I claim is:—

1. A loose leaf binder of the character described, comprising a back and cover-boards hinged to said back; pintle barrels located at or near the junctions of the back and cover-boards and provided with openings to receive

connecting links; links extending between said barrels and having their ends seated in the openings therein; pintles carried by said barrels and extending through the link ends; a bar connecting the pintles of one barrel and serving to move them into and out of engagement with the links, said bar being provided with a seat for a locking bolt; a lock secured to the cover-board in proximity to said bar and having a spring pressed bolt adapted to enter the seat therein; and a detent movable into position to prevent projection of the bolt to locking position when withdrawn therefrom and until the pintle bar is moved to pintle-withdrawing direction a distance sufficient to disengage said detent from the locking bolt.

2. A loose leaf binder of the character described, provided with leaf-carrying links and with pintles for attaching the ends of said links to the cover-boards of the binder; a bar connecting the pintles for one end of said links, provided with a seat to receive a bolt; a key-controlled spring pressed bolt movable into and out of said seat and serving to lock and to release the pintles carried by said bar; and a detent movable into engaging relation with the lock-bolt to hold it against projection when retracted by the key, and releasable by the pintle-carrying bar when said bar is moved a predetermined distance in pintle-releasing direction.

3. In a loose leaf binder of the character described, and in combination with a pintle-carrying bar having a seat to receive a locking bolt; a lock having a spring pressed bolt tending to move automatically outward to enter the seat of said bar; and a detent tending to move automatically into holding relation with said bolt when the same is retracted by the key of the lock, the pintle-carrying bar serving when moved in pintle-withdrawing direction, to remove the detent from its bolt-holding adjustment and thus to permit projection of the bolt sufficient to prevent return of the detent to bolt-holding position, and to enable said bolt to exert frictional pressure upon the bar, tending to prevent accidental longitudinal movement thereof.

4. In a loose leaf binder of the character described, and in combination with a pintle-carrying bar having a seat to receive a locking bolt; a lock having a spring pressed bolt tending to move automatically outward to enter the seat of said bar; a detent tending to move automatically into holding relation with said bolt when the same is retracted by the key of the lock, the pintle-carrying bar serving when moved in pintle-withdrawing direction, to remove the detent from its bolt-holding adjustment and thus to permit projection of the bolt sufficient to prevent return of the detent to bolt-holding position, and to enable said bolt to exert frictional pressure upon the bar, tending to prevent accidental

longitudinal movement thereof, said bar further serving when moved in pintle-inserting direction to bring the bolt-receiving seat into alignment with the bolt to permit such bolt to enter said seat.

5. In a loose leaf binder of the character described, leaf-carrying links; a pintle bar for holding said links, having a bolt-receiving seat in its edge; a lock having a spring-projected bolt to enter said seat when the bar is moved to pintle-engaging position; a key for withdrawing the lock bolt from its seat; a detent for engaging the lock bolt when retracted and holding said bolt out of the path of the pintle bar, said detent extending into the bolt seat in said bar and thus into the path thereof, the bolt seat in the pintle slide being so located that its end wall shall pass over the lock bolt as the pintle bar begins its 20 pintle-releasing movement and shall engage and force back the detent as such releasing movement terminates, thus releasing the locking bolt and permitting it under the urge of its spring to press against the pintle bar and 25 prevent accidental movement thereof in pintle-engaging direction.

6. A loose leaf binder comprising a back and cover boards hinged to said back; pintle barrels carried by said cover boards and having openings to receive the ends of leaf-carrying links; pintles mounted in said barrels; links bridging the space between said barrels and perforated at their ends to receive the pintles of the respective barrels; a bar carrying the pintles of one of said barrels and provided with a seat to receive a locking bolt; a lock carried by the cover board to which said barrel is secured, having a spring-projected bolt to enter the seat in the pintle bar; and a spring-pressed detent for holding the lock bolt in its retracted position when the pintle bar begins and until it completes its pintle-releasing movement, said detent being in the path of movement of the pintle bar and removable from bolt-retaining position by the pintle slide as the latter completes its movement in pintle-releasing direction.

7. A loose leaf binder of the link and pintle type, comprising a plurality of leaf-carrying links; a bar carrying pintles for attaching said links to the binder and for releasing the same, said bar being provided with a seat to receive a locking bolt; a locking bolt adapted automatically to enter the seat when said seat is brought into register with said bolt; and a detent engageable with the locking bolt to hold it in its retracted position during partial pintle-releasing movement of the pintle bar, and disengagable from said bar upon completion of its pintle-releasing movement.

8. A loose leaf binder comprising a plurality of leaf-carrying links, pintles for attaching the ends of said links to the binder, a pintle bar connecting the pintles for corre-

sponding ends of said links and provided with a seat, a lock bolt, spring means tending to project said bolt into said seat to lock the pintle bar against endwise movement, key-actuated means for retracting the bolt, retaining means separate from the key-actuated means for holding the bolt in retracted position to permit removal of the key without relocking the pintle bar.

9. A loose leaf binder comprising a plurality of leaf-carrying links, pintles for attaching the ends of said links to the binder, a pintle bar connecting the pintles for corresponding ends of said links and provided with a seat, a lock bolt, spring means tending to project said bolt into said seat to lock the pintle bar against endwise movement, key-actuated means for retracting the bolt, and retaining means separate from the key-actuated means for holding the bolt in retracted position to permit removal of the key without re-locking the pintle bar, said retaining means lying in the path of movement of a portion of the pintle bar and adapted to be moved from its bolt-retaining position by contact of the pintle bar.

10. A loose leaf binder comprising a plurality of leaf-carrying links, pintles for attaching the ends of said links to the binder, a pintle bar connecting the pintles for corresponding ends of said links and provided with a seat, a lock bolt, spring means tending to project said bolt into said seat to lock the pintle bar against endwise movement, key-actuated means for retracting the bolt, and retaining means separate from the key-actuated means for holding the bolt in retracted position to permit removal of the key without relocking the pintle bar, said retaining means lying in the path of movement of a portion of the pintle bar and adapted to be moved from its bolt-retaining position by contact of the pintle bar during longitudinal movement of the latter in a direction to release the leaf-carrying links from engagement with the pintles.

11. A loose leaf binder comprising a plurality of leaf-carrying links, means for attaching said links to the binder including a member having a seat, a bolt reciprocable in said seat for locking said member, and a rockable detent to engage and be disengaged from the bolt.

12. A loose leaf binder comprising a plurality of leaf-carrying links, means for attaching said links to the binder including a member having a seat, a bolt reciprocable in said seat for locking said member, and a rockable detent to engage and be disengaged from the bolt, said rockable detent lying in the path of movement of said member so as to be rocked thereby to release the bolt.

In testimony whereof I have signed my name to this specification.

JOHN L. McMILLAN. 130
